Primary Examiner — Eric L Goodman*Assistant Examiner* — Amy C Wierenga(74) *Attorney, Agent, or Firm* — Shook, Hardy and Bacon L.L.P.(57) **CLAIM**

The ornamental design for a jacket, as shown and described.

DESCRIPTION

FIG. 1 is a right front perspective view of a jacket according to the present design;

FIG. 2 is a right front perspective view of an alternative configuration of the jacket in which a zipper flap is partially lifted to reveal a zipper fastener;

FIG. 3 is a front view thereof;

FIG. 4 is a right side view thereof;

FIG. 5 is a left view thereof; and,

FIG. 6 is a back view thereof.

The evenly spaced broken lines shown in the drawings are directed to environment, are for informational purposes only, and form no part of the claimed design.

The long and short broken lines are boundary lines, which define the bounds of the claimed design. These boundaries do not exist in reality in the article embodying the design. It is understood that the claimed design extends to these boundaries but does not include the boundaries.
